UNITED STATES PATENT OFFICE.

JOHN B. GLOWACKI, OF CHICAGO, ILLINOIS.

ARM REST FOR CRUTCHES.

Application filed January 3, 1922. Serial No. 526,616.

To all whom it may concern:

Be it known that I, JOHN B. GLOWACKI, a citizen of the Republic of Poland, and a resident of the city of Chicago, in the county 5 of Cook and State of Illinois, have invented certain new and useful Improvements in Arm Rests for Crutches; and I do hereby declare that the following is a full, clear, and exact description of the same, reference 10 being had to the accompanying drawings, and to the numerals of reference marked thereon, which form a part of this specification.

It is an object of this invention to provide 15 an arm rest for use with the top of a crutch which shall be light and yet shall afford ample support.

It is a further object of this invention to provide such an arm rest which shall yield 20 readily to all motions of the user of the crutch and be comfortable in all positions.

It is a further object of this invention to provide a cushion which shall be secured at 25 the top of the crutch by a suspension means.

It is a further object of this invention to provide a metal fixture for securing the arm 30 rest to the crutch.

It is a further object of this invention to provide a cushion at the top of the crutch 35 which shall be readily detachable for cleaning or renewing and shall be securely and safely held in place when attached.

It is a further object of this invention to so form the fixture and cushion at the top 40 of the crutch that only the cushion shall come in contact with the user's person or clothing.

It is a further object of this invention to secure the arm rest to the longitudinal supporting members of the crutch by a means 45 which will not require the ends of the supporting members to be especially shaped.

Other and further important objects of the invention will be apparent from the disclosures in the drawings and the specification.

The invention (in a preferred form) is illustrated in the drawings and hereinafter more fully described.

On the drawings:

Figure 1 is a side view of the top of the crutch.

Figure 2 is an edge view of the same.

Figure 3 is a section upon the line 3—3 of 55 Figure 2.

Figure 4 is a section upon the line 4—4 of Figure 1.

Figure 5 is a section upon the line 5—5 of Figure 1.

Figure 6 is a top plan view.

Figure 7 is an enlarged view showing in section one of the fastening means for the cushion support.

Figure 8 is a section upon the line 8—8 of Figure 7.

As shown on the drawings:

The crutch has the usual upright supporting members 1 which are connected at the top by a casting 2, preferably of aluminum. For this purpose the casting is supplied with 70 sockets 3. The cross-section of these sockets is like that of the members 1 in their finished condition, so that the members do not need to be shaped in order to fit the sockets, but the members 1 may be cut off at whatever 75 length is desired and are at once ready to be inserted into the socket. When inserted they are secured therein by screws 4 which go through the outer walls of the socket. Between the portions of the casting 2 which 80 contain these sockets there is a web 5 preferably of narrow cross-section, so that the edges of the members 1 extend beyond the web 5 and of course the edges of the casting 85 extend still further beyond it.

The casting 2 also has two uprights or horns 6 rising from the portion containing the socket 3. These horns curve outward as they extend upward as best shown in Figures 1 and 3. The upper portions 7 of these 90 horns are reduced in cross-section to provide a pair of flanges 8 on each horn. Upon the outer face of the horns 6 the flanges 8 extend downward a considerable distance but they are continued around the top of the 95 horns and come down upon the inner side thereof a little way as shown at 9.

Through the diminished portion 7 of each horn goes a hole 10. A part of this hole is round but upon the inner face of the horn 100 it is enlarged to a hexagonal shape as shown at 11. In each hole is inserted a sleeve 12 having an enlargement forming a hexagonal head 13 which fits in the enlargement 11 of the hole. The sleeve 12 is threaded and is to cooperate with a screw 14. The head of the screw coats with a washer 15 and the lower end of the recess formed where the cross-section of the horn 6 is reduced, is 105 rounded to fit the edge of this washer, the 110

rounded wall of the recess being continuous with the inner surface of the flanges 8.

Between the washer 15 and the portion 7 is clamped one end of a strip 16 of belting or other flexible material which continues in a curve over the end of the horn and in a loop across to the other horn over its end, and is finally fastened by the washer 15 and screw 14 at the top of the other horn. The strip of belting thus forms a sling or suspension for supporting the cushioning device 17.

The body of this cushioning device is preferably of porous rubber or other elastic material and forms a crescent shaped cushion as shown in Figures 1 and 3 whose cross-section, as shown in Figure 4, is approximately square. In order to secure this cushioning material in place upon the sling 16, the cushion and the sling are surrounded by a cover 18. The cover may be of any suitable material but preferably it is made of leather. It is secured in place by being fitted over the cushion and the seam is then sewed together below the cushion along its edges as shown at 19. As may be best seen from Figures 3 and 4, this seam extends below the center of the cushion next to the sling from one end of the cushion to the other.

Upon its upper face where the edges of the cover 18 meet the sling 16 they are preferably beveled as shown at 20 in Figure 7. The outer corners of the flanges 8 are rounded. The inner edges of the flanges stand flush with the surface of the washer 15. Thus sharp corners or projecting parts that may cause discomfort to the user or unnecessary wear to his clothing are avoided.

In the operation of the device:

When it is desired to assemble a crutch, the longitudinal members 1 are cut off at the desired length and without any further fitting are inserted into the sockets 3 and fastened therein by the screws 4. The cushioning device is previously assembled by sewing the cover 18 over the block of rubber 17 and the sling or the cover may be made round the block 17, leaving sufficient space which is afforded by a groove in the bottom of the block 17, and the belting 16 may be threaded into that space between the cover and the rubber. The ends of the sling 16 have been previously perforated to receive the screws 14. The assembled cushioning device is then secured to the casting 2 by positioning the ends of the sling 16 between the flanges 8, placing the washers 15 over them and inserting the screw 14 into the sleeve 12 through the washers and the strip of belting. When the cover 18 has become soiled or worn the screws 14 are removed and the cushioning device taken off the crutch. By ripping the seam 19 the cover may then be readily removed from the

block of rubber 17 and a new cover put on in its place, or the cover which has been removed may be cleaned and replaced. If desired, the cover may be pulled off the block of rubber without ripping the entire 70 seam. In replacing the cover it is necessary to again sew the seam 19.

Worn out slings, straps or belts 16 may be removed from the cover and replaced by new ones when desired, without ripping off 75 the cover, by simply drawing the straps 16 out of the space between the cushion and the cover 18.

I am aware that many changes may be made and that numerous details of construction may be varied through a wide range without departing from the principles of this invention, and I therefore do not purpose limiting the patent granted otherwise than necessitated by the prior art.

I claim as my invention:

1. A crutch comprising two upright longitudinal members, a casting connecting said members at their upper ends, a cushioning device, and a flexible non-stretching suspension device slidable through said cushioning device with the ends of said suspension device removably secured to said casting to hold the cushioning device suspended in position.

2. In a device of the class described, a loop suspended by its ends, and a cushioning device slidably carried by said loop.

3. A loop suspended by its ends and a crescent-shaped cushioning device removably engaged around said loop.

4. The combination with a loop-shaped suspending device, of a crescent shaped cushioning device seated therein, and a cover surrounding said cushioning device and said suspending device and permitting removal of the suspending device from the cushioning device, and from said cover.

5. The combination with a crutch, of a fixture for the upper end thereof including a cross piece, a cushion, and a strap removably engaged through said cushion and secured to the fixture, the thickness of said cushion at right angles to the plane of the crutch being greater than the thickness of 115 said cross piece.

6. In a crutch, a fixture for the upper end including a cross piece, a cushion, a suspension device removably projecting through the cushion for supporting said cushion above said cross-piece whereby the cushion is free to move at right angles to the plane of the crutch, the thickness of said cushion at right angles to the plane of the crutch being greater than the thickness of 120 said cross-piece.

7. In a crutch, a fixture for the upper end, including two recessed horns, a suspension device including a strap passing over the top of each of said horns and seated

in the recesses thereof to be flush with said horns, fastenings securing said strap to the outer side of each horn, said strap forming a loop between the horns, and a crescent 5 shaped cushion supported in said loop, said fastenings each being above the center of the top of said cushion.

8. A crutch comprising supporting members, a one piece metal casting connecting 10 the same and having arms, the ends of which are provided with recesses, a cushion having a groove therein, a cover enclosing the cushion, a strap projecting through the cover and seated in the cushion groove with

the ends of said strap seated in the arm 15 recesses, washers seated in said arm recesses over the ends of said strap, and removable means for securing the ends of said strap and said washers to said recessed arms with the washers flush with the outer surface of 20 said arms.

In testimony whereof I have hereunto subscribed my name in the presence of two subscribing witnesses.

JOHN B. GLOWACKI.
